LOOSE-LEAF BINDER

Reginald M. Raynolds, Summit, N. J.

Application February 21, 1946, Serial No. 649,140

5 Claims. (Cl. 129—1)

1

This invention relates to loose leaf binders, and aims to provide certain new and useful improvements whereby the leaves when secured in the covers of the folder by means of the binder, are safe against inadvertent opening of the binder and are therefore unable to slip or fall out of the binder, and whereby the binder must be slid out of the covers before the leaves can be detached or before additional leaves can be inserted.

The above broad object as well as additional and more specific objects will become apparent in the following description, wherein characters of reference refer to like-numbered parts in the accompanying drawings. It is to be noted that the drawings are intended for the purpose of illustration only, and that it is neither desired nor intended to limit the scope of the invention necessarily to the specific details of construction shown excepting insofar as they may be deemed essential to the invention.

Referring briefly to the drawings:

Fig. 1 is a plan view of an open folder equipped with the binder of this invention.

Fig. 2 is a bottom end view of Fig. 1.

Fig. 3 is a cross-sectional view taken on the line 3—3 of Fig. 1.

Fig. 4 is a cross-sectional view taken on the line 4—4 of Fig. 5.

Fig. 5 is a view similar to Fig. 1, but with the binder and the leaves bound therein removed.

Fig. 6 is a fragmentary perspective view of the binder per se, partly in section.

Fig. 7 is a fragmentary view similar to the lower portion of Fig. 1, but showing a releasable catch for locking the binder in the folder against sliding out.

Fig. 8 is a fragmentary view similar to the lower portion of Fig. 5, showing the releasable catch above-mentioned.

Fig. 9 is a side view of Fig. 8.

Fig. 10 is a view similar to the upper portion of Fig. 1, showing the manner in which a key lock may be applied to the binder to lock the same and its leaves in the folder against unauthorized withdrawal of the leaves.

Fig. 11 is a side view of Fig. 10.

Fig. 12 is a perspective view of the folder in closed condition.

Fig. 13 is a cross-sectional view taken on the line 13—13 of Fig. 6, showing the binder in opened condition.

Referring in detail to the drawings, the numeral 10 indicates a loose leaf folder consisting of the two boards 11 and the back 12. A metal strip 13 is secured in spaced relationship to the back 12

2

by means of spaced rivets 14 and spacers 15, the longitudinal edges 16 of the strip being beveled substantially as shown, on that side of the strip nearer the back 12.

5 The binder 17 per se is composed of a pair of complementary mutually hinged plates 18 and 18a, the hinge pin thereof being shown at 19. On their backs the plates 18 and 18a have mutually convergent angular extensions or wings 20. The outer edge of the plate 18 has a plurality of spaced open rings 21 anchored to, or formed integral, the said plate edge and extending in the direction of the plate 18a. These rings are adapted to enter and register in openings 22 of the leaves 23 which are to be loosely bound.

In order that the hinged plates 18 and 18a may be mounted within the covers 11, the plates must first be arranged in a common plane, as shown in Fig. 3, whence the binder 17 may be 20 slipped up the rigid strip 13, into the position shown in Fig. 1. In this position, it is to be noted, the strip 13 serves as a bar to any movement of the plates 18 and 18a about their hinge pin 19, so that there is no possibility of disengaging the 25 rings 21 from the leaves 23 while the binder 17 registers on the strip 13. When the binder 17 has been slid off the strip 13, the plates 18 and 18a may be readily swung about the pin 19 into the 30 position shown in Fig. 13, so that the leaves 23 may be removed at will.

In order to prevent inadvertent sliding of the binder 17 off the strip 13 and hence a possible separation of the leaves from the binder, a releasable locking means has been provided in the 35 form of a resilient finger or spring 24 anchored at 25 to the back 12 and having a button 26 on its free, upwardly extending end. The button 26 normally lies in the path of the binder 17, as shown in Figs. 7 and 9; depression of the button 40 26 clears this path so that the binder 17 may be withdrawn when desired.

The device as described may be further provided with a key lock 27 mounted on the strip 13 or the back 12, and the binder 17 may be provided with an extending tongue 28 having a slot 29 therethrough adapted to register in a complementary recess in the lock housing. The lock would of course be provided, in the usual manner, with a bolt, not shown, adapted to be engaged in 50 the slot 29 upon turning of the key 30 in one direction and to be withdrawn upon turning the key in the reverse direction. In this manner the binder 17, with the leaves bound therein, could be actually locked against unauthorized withdrawal of 55 any of the leaves 23.

To facilitate insertion of the lower end of the strip 13 into the binder 17, the strip is tapered as shown at 31.

It is apparent from the invention as above set forth that a loose leaf binder has been provided wherein the possibility of inadvertent withdrawal of the leaves is eliminated.

Obviously, modifications in form and structure may be made without departing from the spirit and scope of the invention.

I claim:

1. In an article of the class described comprising a folder including a pair of boards and a back joining the boards, a rigid strip mounted on said back in spaced relationship therewith, a binder comprising a pair of mutually hinged plates having their outer longitudinal edges bent back at an angle to form wings, one of said plates having open rings anchored at one end thereon and extending in the general direction of the other of said plates around the forward surfaces of said plates, said plates being adapted to be mutually pivoted into positions where said plates lie in a common plane and in the said positions being adapted to be slid over said strip with said wings engaging the edges of said strip, the free ends of said rings in the last-named position of said binder terminating substantially at the outer longitudinal edge of the other of said rings.

2. The device set forth in claim 1, one end of said strip being tapered.

3. The device set forth in claim 1, having releasable means normally preventing said binder from sliding off said strip.

5 4. The device set forth in claim 1, having a resilient finger anchored at one end on said back and extending angularly upward therefrom into the path of said binder with respect to the sliding of said binder off said strip, said finger thereby normally preventing said binder from sliding off said strip.

10 15 20 5. The device set forth in claim 1, having a resilient finger anchored at one end on said back and extending angularly upward therefrom to a position substantially in the line of said binder with respect to sliding said binder off said strip, said finger having a button on the free end normally positioned at said line as an obstruction to the said sliding off of said binder.

REGINALD M. RAYNOLDS.
